UNITED STATES PATENT OFFICE.

GEORGE W. SANBORN, OF UTICA, NEW YORK.

CLOTHES-PRESSING MACHINE.

1,169,873.

Specification of Letters Patent.

Patented Feb. 1, 1916.

Application filed April 1, 1913. Serial No. 758,229.

To all whom it may concern:

Be it known that I, GEORGE W. SANBORN, of Utica, in the county of Oneida, in the State of New York, have invented new and useful Improvements in Clothes-Pressing Machines, of which the following, taken in connection with the accompanying drawings, is a full, clear, and exact description.

This invention relates to certain improvements in machines for cleaning, sponging and pressing garments and other fabrics by direct pressure as distinguished from ironing machines and similar apparatus employing sad irons or equivalent polishing or smoothing device for rubbing contact with the fabric.

The main object is to increase the range of usefulness of this class of machines according to the nature or quality of the work operated upon so that the same machine may be used not only for cleaning, sterilizing, pressing and restoring the nap of various kinds of outer garments, but also for sponging, steaming and smoothing whole cloth, knit underwear and similar fabrics with or without pressing according to the nature of the material or requirements for different materials.

I am aware that various forms of machines have been proposed and put into use for applying steam to the upper surface of the garment while the latter is subjected to mechanical pressure through the medium of a vertically movable press head, having a foraminous bottom plate through which the steam is allowed to pass and thereby to soften and restore the nap and to expedite the drying of the garment by the rapidity of evaporation of the steam and without leaving excessive moisture of condensation in the garment, but I have discovered that practically the same results may be accomplished by a proper distribution of the steam in a steam-receiving buck having a foraminous cover or press plate coacting with an imperforate or non-foraminous press plate of a superposed press head manipulated in substantially the same manner as the usual foraminous press head except that the steam is applied to the under surface of the garment or cloth simultaneously with the application of mechanical pressure by the imperforate press head, whereby the steam is held back from passage through the fabric leaving just sufficient moisture in such fabric to soften the nap and allowing the excess water of

condensation to fall by its own gravity back into the steam chamber of the buck from which it drains off through a suitable drainage pipe, thus preventing the application of excess moisture to the fabric.

Another object is to construct the inside of the press plate of the buck in such manner as to condense and throw back any excess moisture which may be carried into the buck by the steam, thereby obviating the necessity for steam deflectors or extra steam-distributing plates.

A further object is to neutralize the force of the steam pressure upon its entrance into the pressing element by delivering such steam into opposed pipes within the buck and providing the adjacent faces of such pipes with orifices facing each other so that the steam jets from one pipe will be impinged against those emerging from the other pipe.

A still further object is to provide one end of the buck with a gripping device for holding the garment as, for example, trousers or skirts while being stretched out upon the surface of such buck preparatory to steaming, sponging or pressing.

Another object is to equip the machine with a vacuum cleaner connected to the same pipe which supplies steam to the pressing elements and having a suction nozzle adapted to be moved by the user over the entire surface area of the buck for removing dust and other foreign matter therefrom.

Other objects and uses will be brought out in the following description.

In the drawings—Figure 1 is a perspective view of the entire cleaning and pressing apparatus including the steam generator. Fig. 2 is a top plan of the same apparatus exclusive of the boiler and vacuum cleaner showing a portion of one of the bearings for the movable head in section, said head being shown approximately in its pressing position. Fig. 3 is a transverse vertical sectional view through the upper portion of the machine taken on line 3—3, Fig. 2. Fig. 4 is a longitudinal vertical sectional view through the pressing elements taken on line 4—4, Fig. 2. Fig. 5 is an inverted plan of the detached pressing plate for the buck, showing the alternating ribs and channels and also the perforations therein. Fig. 6 is a longitudinal vertical sectional view through the shoulder buck taken on line 6—6, Fig. 2. Fig. 7 is a longitudinal verti-

cal sectional view on the line 7—7, Fig. 2, through one end of an auxiliary smoothing buck for straightening and smoothing the legs of trousers, sleeves of coats and similar uses, showing also its turning connection with the adjacent portion of the table top. Fig. 8 is a top plan of the main body of the buck with the pressing plate removed showing the arrangement of the steam-distributing pipes therein.

In order that my invention may be clearly understood, I have shown a main supporting frame —1— as provided with a table top —2— and an upstanding bracket —3— upon which is mounted a hollow buck —4—, said frame being also provided with upwardly projecting brackets —5— between and upon which is journaled a rocking frame —6— carrying a hollow vertically movable press head —7—.

The frame —1— may be of any suitable size or form capable of supporting the various mechanisms exclusive of the boiler at a proper elevation and sufficiently secure to resist the strains to which such mechanisms are subjected, the table —2— being preferably made of enameled metal of suitable area and secured in a horizontal plane upon the frame some distance beneath the pressing elements and serve as a temporary support for the garments while being prepared for cleaning, sponging or pressing and also to protect such garments from trailing contact with underlying mechanisms which may be more or less soiled by dust or lubricants.

The bracket —3— is preferably U-shaped having its lower arm secured to the main supporting frame and its upper arm disposed horizontally for receiving and supporting the buck —4— which may be rigidly secured thereto so as to lie in a horizontal plane substantially parallel with but some distance above the table top —2—, thereby allowing garments of various forms to be drawn over either end thereof, the upright portion of the bracket being preferably hollow for receiving and concealing a steam supply pipe —8— and a drainage pipe —9— leading respectively from the interior of the buck to a steam generator —A— and to a waste pipe or receptacle (not shown).

The buck —4— preferably consists of a hollow cast metal body elongated laterally or from side to side of the machine and tapered toward one end (preferably toward the right hand end, Fig. 1) and centrally supported upon the upper face of the bracket —3— so as to cover the open upper end of the hollow hub of the bracket to afford direct connection of the supply and drainage pipes —8— and —9— with the underside thereof.

The upper side of the buck is provided with a substantially flat cast metal presser plate —10— of approximately the same

form and area as the main body and having its marginal edges secured thereto by suitable fastening means as screws —11— to cover the top of the steam chamber as —12—. This press plate —10— is provided on its underside with a series of lengthwise V-shape ribs —13— and intervening grooves or channels —14— alternating therewith, said plate being also provided with a series of rows of apertures —15— leading from the base of the grooves or channels —14— through the upper face of the plate to allow the steam to pass therethrough and thence through a superposed pad or cover —16— which is drawn tightly across the upper face 80 of the buck and secured across the lower face thereof by suitable lacing —17— similar to that shown in Fig. 2 for the press cloth of the superposed head.

The steam pipe —8— is connected to a cross pipe or header —18— within the chamber —12—, said cross pipe being provided with opposite longitudinally extending branch pipes —19— running along the longitudinal edges of and within the buck 90 and having their adjacent faces provided with relatively small orifices or apertures —20— for directing the escaping jets of steam toward and against each other within said chamber and thereby effectively neutralizing the force of the steam and evenly distributing it under even pressure throughout the area of the perforated press plate —10— through which it emerges. That is by opposing the jets of steam emerging from 100 the distributing pipes —19— so that they impinge one against the other, tends to reduce the pressure and to distribute the steam in a dense cloud throughout the whole interior area of the chamber and inasmuch 105 as the steam is admitted only for an instant, it is evident that it will pass through the foraminous plate and pad to the surface of the garment or fabric only under its own buoyancy for the reason that the steam 110 would be shut off before the steam chamber in the buck was completely filled under the normal pressure of the entering steam. I have taken advantage of this condition to further reduce the moisture content of the 115 steam by providing the V-shaped ribs and channels in the underside of the press plate for the purpose not only of increasing the surface area against which the steam impinges upon its entrance into the steam chamber and thereby aiding in the condensation of the highly saturated steam but also preventing the direct passage of this highly saturated steam directly through the apertures leading from the base of the grooves 120 through the surface of the pressing plate. These two features, namely: the opposing of the opposite jets of steam to each other to neutralize the normal steam pressure upon 125 its entrance into the steam chamber of the 130

buck, and also the provision of the ribs referred to, constitute important features of my invention in that it materially reduces the moisture content of the steam which passes through the perforations in the 5 pressing plate to the under surface of the garment and thus avoids excessive saturation of the garment and permits it to be dried quickly by the steam-heated buck and 10 press head, it being understood that the water of condensation gravitates instantly to the bottom of the buck and is immediately drained off through the drainage pipe —9— to keep the interior of the buck free from 15 accumulations of moisture.

The bearings —5— upon which the supporting frame —6— for the buck —4— is mounted are located some distance to the rear of and substantially parallel with the longitudinal center of the buck so as to cause the 20 press head —7— to move vertically in parallelism therewith, the axis of movement of the press head being nearly coincident with the plane of the upper surface of the buck to 25 cause the head to lift bodily some distance away from the upper surface of said buck when drawn upwardly to its inoperative position, thereby allowing the garments or cloth to be spread out by hand upon said 30 buck where it may be inspected throughout its area and carefully prepared for the pressing operation with the assurance that the buttons, pocket flaps, lapels and the like will be properly arranged. The distance between 35 the axis and longitudinal center of the head is substantially the same as the distance between the same axis and longitudinal center of the buck.

The press head also consists of a hollow 40 cast-metal body of substantially the same form and size in top plan as that of the buck and its upper side is secured to the front side of the rocking frame —6— so as to cause its presser face to lie in substantially 45 the same plane as that of the upper face of the buck when in its pressing position as shown more clearly in Figs. 3 and 4, thereby bringing the longitudinal center of the press head in coincidence with that of the buck.

The interior chamber, as —21— of the 50 press head is adapted to receive steam from the same source of supply as the buck —4— and is approximately coincident with the area thereof, but the lower side, constituting 55 the press plate, is imperforate to prevent the passage of steam therethrough, the lower surface of the press plate being covered by a press cloth —22— drawn tightly thereacross and having its marginal edges secured across 60 the top of the head by a suitable lacing —23— shown more clearly in Fig. 2. The steam chamber is also provided with a steam inlet pipe —24— and a drainage pipe —25—, both of which have turning connection with 65 suitable distributing heads —26— and

—27— on the outer ends of the opposite bearings —5— coaxial with the axis of movement of the press head —7— to which the pipes —24— and —25— are rigidly connected, thus permitting the movement of the 70 press head without straining the joints. The distributing head —26— is connected by a branch pipe —28— to a main supply pipe —29—, said branch and main supply pipes being provided respectively with normally 75 open valves —30— and —31— for controlling the flow of steam to the press head although the main purpose is to keep these valves open for maintaining live steam in the steam chamber —21— for heating the 80 pressing head. The distributing head —27— for the drainage pipe is also connected by a branch pipe —32— to a main drainage pipe —33— which also receives the drainage from the pipe —9— of the buck —4—.

The main steam supply pipe from the boiler preferably extends downwardly at the rear of and lengthwise under the table, as shown more clearly in Fig. 1, and is provided with the branch pipe —8— leading to the 90 interior of the buck and with an additional branch supply pipe —34— leading to the interior of a shoulder buck —35— which also consists of a hollow cast-metal body mounted upon a hollow standard or bracket —36— on the table —2— at one end of the buck —4—, said hollow standard serving to receive and conceal a portion of the branch supply pipe —34— extending therethrough and also a 95 branch drainage pipe —37— communicating 100 with the main drainage pipe —33—.

The branch supply pipe —8— leading to the interior of the buck —4— is provided with a normally closed valve —38— near its connection with the main supply pipe —29— 105 and adapted to be opened by means of a pedal lever —39— and link —40— connecting said pedal lever with a crank arm —41— on the stem of the valve, said pedal lever being fulcrumed at —42— to the lower end 110 of one of the front legs of the frame —1— so that when the front end of the pedal lever —39— is depressed it will open the valve —38— against the action of a retracting 115 spring —43—. In like manner, the supply pipe —34— for the shoulder buck —35— is provided with a normally closed valve —45— having its stem provided with a crank arm —46— which is connected by a link —47— to a separate pedal lever —48— on the other 120 front leg of the frame so that by depressing the front end of the lever —48—, the valve —45— will be opened against the action of a retracting spring —49— to admit steam to 125 the buck —35—. This buck is employed to give form to the shoulders and collars of coats, vests and similar garments and for this purpose its upper side is made to conform as nearly as possible to the natural 130 form of the shoulders and collars of such

- garments, but is perforated and covered with a pad —50— in a manner similar to that described for the main buck —4—. The inner side of the top of the shoulder buck is also 5 provided with alternating V-shape ribs —51— and intervening V-shape grooves —52— for the same purpose as the ribs —13— and grooves —14— in the main buck —4—.
- 10 The steam supply pipe —34— extends into the steam chamber of the buck —35— and is connected to a header pipe —53— having opposed branch pipes —54— provided in their adjacent faces with perforations —55— 15 for the same purpose as the branch pipes —19— and perforations —20— in the main buck.

The ends of the branch pipes —19 and —54— in the bucks are closed respectively 20 by caps —19'— and —54'— so as to allow the steam to escape therefrom into their respective chambers only through the apertures —20— and —55—.

The gripping device, previously mentioned for temporarily holding a garment, such as trousers and the like, while spreading them out upon a buck preparatory to sponging, cleaning and pressing, preferably 25 comprises an extension plate —44— and a 30 rocking cam shaft —56—. This gripping device is adapted to be applied to the large end of the buck to swing vertically to and from the plane of the upper surface thereof and for this purpose is provided with opposite 35 longitudinally extending arms pivoted at —44'— to opposite sides of the adjacent large end of the buck so as to swing vertically to bring the upper face of the plate in substantially the same plane as that of the 40 buck —4—, as shown more clearly in Figs. 1, 2 and 4, where it is held by a removable locking pin —4'— loosely inserted in an aperture in the adjacent side of the buck or it may be held in this position by any other 45 movable detent not necessary to herein illustrate or describe.

By removing the pin —4'—, the entire gripping device may be rocked downwardly beneath the upper surface of the buck.

50 The cam shaft —56— is journaled at one end in a suitable bearing —56'— on the rear side of the plate —44— and is extended radially in one direction toward the plate —44—, the lower edge being substantially 55 straight and parallel with the upper surface of said plate to coöperate therewith for gripping and holding a portion of the garment.

The supporting frame —6— for the press 60 head —7— may be operated to force the press head downwardly by any suitable means consisting in this instance of a forwardly and rearwardly extending pedal lever —57— having its rear end fulcrumed at —58— upon the rear portion of the

frame —1— and its front end movable vertically in a slot —59— in the front portion of the frame, as shown more clearly in Fig. 1, and normally held in its up-position by a retracting spring —60—. This lever 70 —57— extends some distance to the rear of its fulcrum and is pivotally connected to an up-standing link —61— at the rear of the machine, said link being connected to the lever by a spring —62— acting to draw the 75 upper end of the link forwardly into interlocking engagement with a stud or pin —63— on the rear end of the rocking frame —6— as shown more clearly in Fig. 3. The upper end of the link —61— extends some 80 distance above the normal position of the stud or pin —63— when the press head is rocked upwardly, thereby allowing the pin to rest against the front edge of the link, the press head being adapted to be drawn forwardly and downwardly to approximately its pressing position by means of a handle —66— thereon until the stud or pin —63— is brought into interlocking engagement with a recess —63'— in the upper front 90 edge of the link, whereupon the further movement of the press head to its pressing position is effected by the downward pressure of the foot upon the front end of the lever —57—.

The handle —66— is slideable forwardly and rearwardly in suitable ways —67— on the top of the press head —7— and is connected by a rearwardly extending link —68— to the upper end of a tripping pawl 100 —69— which is pivoted at —70— to the rear end of the rocking frame —6— just in front of the upper end of the link —61— with which it is adapted to engage so that by drawing the handle forwardly against 105 the action of its retracting springs —71—, the lower end of the tripping pawl —69— will engage and trip the link —61— from locking engagement with the stud —63—, thereby allowing the spring —60— to return the press head to its normal up-position.

In addition to the bucks —4— and —35—, the machine is equipped with an additional buck —80— somewhat narrower than the main buck but tapered longitudinally toward one end and having its outer end pivoted or journaled in a suitable bearing —81— upon and near one end of the table top —2— so that it may swing horizontally 115 about its vertical axis for the reception of trouser legs, coat sleeves and the like which it may be desired to straighten or smooth thereon, the upper surface of said buck —80— being provided with a pad —82— 120 similar to the pads —11— and —22— for protecting the garment against soiling.

In addition to the mechanisms previously described, the machine is provided with a suitable vacuum cleaning device —90— 130

5 mounted upon the frame —1— as shown in Fig. 1 and adapted to be operated by a small steam engine (not shown) connected to the main supply pipe —29—, said vacuum cleaner having a flexible suction hose —91— terminating in a suction nozzle —92— which may be moved by the operator across the entire surface area of either of the bucks for removing the dust and other foreign matter from the clothes which may be supported thereon.

10 The operation of my invention will now be readily understood upon reference to the foregoing description and the accompanying drawing and, although I have described minutely the various parts of the machine, it is evident that these parts may be substituted by equivalents, without departing from the spirit of this invention.

15 20 What I claim is:

1. In a clothes pressing machine, a hollow elongated buck having a horizontally disposed top provided in its underside with continuous lengthwise channels from end to end thereof, and lengthwise rows of perforations leading from the bases of said channels through the upper face of the top throughout the lengths of said channels.

2. In a clothes pressing machine, a hollow elongated buck having a horizontally disposed top provided in its underside with continuous lengthwise channels from end to end thereof, and lengthwise rows of perforations leading from the bases of said channels through the upper face of the top throughout the lengths of said channels, and means for directing jets of steam in opposed directions across the under side of the top and transversely of the channels.

3. In a clothes pressing machine, two elongated pressing elements, one above the other, the lower element having a horizontally disposed top and an underlying steam

chamber substantially coextensive therewith, said top having lengthwise parallel rows of 45 perforations therethrough from end to end of the chamber and continuous lengthwise channels in its under side following the rows of perforations and communicating therewith.

4. In a clothes pressing machine, two elongated pressing elements, one above the other, the lower element having a horizontally disposed top and an underlying steam chamber substantially coextensive therewith, 55 said top having lengthwise parallel rows of perforations therethrough from end to end of the chamber and continuous lengthwise channels in its under side following the rows of perforations and communicating therewith, and steam pipes running along opposite sides of and within said chamber and perforated through their inner sides for projecting jets of steam across the under side of the top transversely of said channels and 60 rows of perforations.

5. In a clothes pressing machine, two elongated pressing elements, one above the other, the lower element having a horizontally disposed top and an underlying steam 70 chamber substantially coextensive therewith, said top having lengthwise parallel rows of perforations therethrough from end to end of the chamber and continuous lengthwise channels in its under side following the 75 rows of perforations and communicating therewith, the inner faces of the portions of the top between the channels being V-shaped in cross section to deflect the steam to adjacent rows of perforations.

In witness whereof I have hereunto set my hand this 28th day of March 1913.

GEORGE W. SANBORN.
